UNITED STATES PATENT OFFICE.

JOHN GREENWOOD, OF ROCHESTER, NEW YORK.

MACHINE FOR CROZING AND CHAMFERING STAVES.

SPECIFICATION forming part of Letters Patent No. 373,736, dated November 22, 1887.

Application filed May 25, 1887. Serial No. 239,352. (No model.)

To all whom it may concern:

Be it known that I, JOHN GREENWOOD, of the city of Rochester, in the county of Monroe and State of New York, have invented new and useful Improvements in Machines for Crozing and Chamfering Staves, of which the following is a specification.

This invention relates to a machine by which detached staves are crozed and chamfered; and it has for its object to produce a machine by which these operations can be effected without splitting or chipping the ends of the staves. In machines of this class as heretofore constructed this has been the principal difficulty, and the staves have therefore been generally set up in barrel form, and were then crozed and chamfered in this condition.

My invention consists of the improvements which will be hereinafter fully described, and pointed out in the claims.

In the accompanying drawings, consisting of two sheets, Figure 1 is a front elevation of my improved machine. Fig. 2 is a top plan view of the same. Fig. 3 is an end elevation thereof. Fig. 4 is a vertical cross-section in line $x-x$, Fig. 1, on an enlarged scale. Fig. 5 is a longitudinal fragmentary sectional elevation, on an enlarged scale, of one end of the machine. Fig. 6 is a perspective view of one of the arms on which the staves are supported.

Like letters of reference refer to like parts in the several figures.

A A' represent the end frames of the machine; a, a longitudinal bar connecting the top portions of said frames, and a' a² longitudinal bars connecting the end frames on their front and rear sides.

B represents the cutter-heads, to which the crozing-knives b and chamfering-knives b' are secured, and which are arranged at opposite ends of the machine and secured to horizontal shafts b². The latter are journaled in bearings c c, secured to a bed-plate, C, which slides in horizontal ways c', formed on brackets C'. These brackets are formed on the end frames, A A', so as to project from the outer sides of the latter. c² represents pulleys, which are secured to the shafts b² between the bearings c c and driven by belts c³.

d represents the main shaft of the machine, 50 arranged horizontally and journaled in bearings d' d², mounted in the end frames, A A'.

E represents the driving-pulley, mounted loosely on the shaft d on the outer side of the end frames, A A'; and e represents a pinion secured to the pulley E on the inner side thereof. 55

E' represents a loose pulley mounted on the extended hub of the pulley E.

f represents a horizontal counter-shaft arranged below the main shaft d, and journaled 60 in bearings f' f², arranged in the end frames, A A', below the bearings d' d², and in an additional bearing, f³, which is secured to the horizontal tie-rods f⁴ on the outer side of the end frame A.

F represents a gear-wheel secured to the end 65 of the counter-shaft f and meshing with the pinion e.

g represents a pinion secured to the counter-shaft f midway between the end frames, A 70 A'; and G is a gear-wheel secured to the main shaft d above the pinion g and meshing therewith. The bearings d' f' d² f² are arranged, respectively, in vertical ways h h', formed in the end frames, A A', and the upper bearings, 75 d' d², are supported on the lower bearings, f' f², by vertical rods h³. The lower bearings, f' f², are supported in the end frames by springs h⁴, which permit both sets of bearings and the parts supported therein to yield downwardly 80 when a stave of unusual thickness passes through the machine.

H H represent semicircular convex guide-bars secured with their lower ends to the longitudinal front and rear bars, a' a², of the 85 frame, and extending over the main shaft d at right angles to the frame and on opposite sides of the gear-wheel G.

I I and J J represent segmental concave guide-bars secured to the under side of the top 90 bar, a, between the guide-bars H and the side frames, A A', the guides I being lower than the guide-bars H and the guides J lower than the guides I, as clearly represented in Fig. 5.

K represents a stave operated upon and arranged upon the guide-bars H and below the guides I J, whereby the proper bulge or curve is imparted to the stave. The guides J, which

are arranged near the end frames and nearest the ends of the stave, are provided with lances or stationary knives *j*, which cut into the ends of the staves from the outer side and level the 5 staves, the cut being so deep that it is intersected by the chamfering knives, whereby the projecting end of the stave is severed.

L L represent the feed-wheels secured to the shaft *d* near the outer guides, J, and on the 10 inner sides thereof. These wheels are provided on their inner sides with feed-dogs *l*.

M M represent supporting-wheels mounted loosely on the extended hubs of the feed-wheels, and having their faces arranged near the outer 15 guides, J, so that the ends of the staves are chamfered between the wheels M and the guides J.

N N represent horizontal bars which support the staves as they are introduced into the 20 machine, and which serve the purpose of a feed-table. These bars are secured with the outer ends to the front bar, *a'*, of the frame, and are provided at their inner ends with rings or hubs *n*, which encircle the hubs of 25 the feed-wheels L, and which are retained thereon by collars *n'*, secured to the shaft *d*.

O represents segmental guides secured to the outer sides of the supporting-bars N, and curved concentric with the shaft *d* at such a distance 30 from the latter that the similarly-curved depending portions or tails *l'* of the dogs *l* will ride over the curved faces of these guides, as represented in Fig. 4, and be thereby caused to clamp the staves placed against the faces of 35 the loose supporting-wheels M. A stave being placed edgewise upon the bars N and against the faces of the wheels M, as represented in Fig. 4, the dogs *l*, as they move upwardly on the front side of the machine, seize the stave 40 and carry it upwardly and under the guides I and J until the tails of the dogs *l* pass beyond the upper ends of the segmental guides O, when the overhanging tails cause the dogs to turn on their pivots and release the stave. 45 Each stave, after having been released by the dogs, is moved forward between the wheels M and the guides I and J by the next succeeding stave which is elevated by the dogs, so that when the staves pass the cutters their jointed 50 faces are held in as close contact by the pressure exerted by the last stave inserted and moved forward by the dogs as they would be if they were set up in a barrel. This prevents the edges of the staves from splitting or chipping. 55 The finished staves are delivered from the guides I and J upon an inclined table, P, on the rear side of the machine. The loose supporting-wheels M permit the staves in the machine to remain stationary when no stave 60 is fed in, while the feed-wheels L continue to rotate.

The feed-bar N, feed-wheel L, and the loose wheel M mounted thereon are adjustable at each end of the machine lengthwise of the 65 shaft *d*, in order to change the position of these parts as may be required to operate

upon staves of different lengths, and the concave guides I and J are similarly adjustable on the top bar, *a*.

I am aware that it is not new to feed detached staves successively between straight guides to crozing and chamfering cutters, and I do not claim a machine of such construction, which is essentially different from my construction, as in that case the staves touch only with the outer edges of their jointed faces, leaving these faces practically unsupported during the operation of chamfering and crozing, which frequently results in splitting or chipping the staves. 70 75 80

I claim as my invention—

1. The combination, with the convex and concave guides bearing against opposite sides of the staves, of feed-wheels, whereby the staves are successively fed between the guides, 85 and crozing and chamfering cutters operating against the inner sides of the staves passing between said guides, substantially as set forth.

2. The combination, with the elevated convex guides bearing against the inner side of the staves, and depressed concave guides bearing against the outer side of the staves, of feed-wheels arranged concentric with said guides, and whereby the staves are successively fed between the said guides, and crozing and chamfering cutters operating against the inner sides of the staves passing between said guides, substantially as set forth. 90 95

3. The combination, with the convex and concave stave-guides and the crozing and chamfering cutters, of wheels provided with feed-dogs, whereby the staves are successively fed between said guides and moved past said cutters with their jointed faces in close contact, substantially as set forth. 100 105

4. The combination, with the stave-guides and cutters, of feed-wheels L, provided with movable feed-dogs *l*, and fixed guides O, against which said dogs bear and by which said dogs are closed on the staves and released, substantially as set forth. 110

5. The combination, with the stave-guides, of the feed-wheels L, whereby the staves are fed between the guides, and the loose wheels M, 115 whereby the staves are supported, substantially as set forth.

6. The combination, with the stave-guides, of the feed-wheels L, whereby the staves are fed between the guides, the loose wheels M, 120 mounted on the same and supporting the staves, and fixed stave-supporting bars N, projecting beyond the feed-wheels and loose supporting-wheels and receiving the staves, substantially as set forth. 125

7. The combination, with the feed-wheels L and loose supporting-wheels M, mounted on the same, of the convex guides H, concave guides J, stationary knives *j*, and rotary cutter-heads B, substantially as set forth. 130

8. The combination, with the stave-guides, feed-wheels L, and their shaft *d*, of the coun-

ter-shaft f , end frames, A A', provided with vertical ways, connected bearings $d' f'$ and $d^2 f^2$, in which said shafts are journaled, and springs whereby the bearings are enabled to

5 yield, substantially as set forth.

9. The combination, with the cutter-heads B, stationary stave-guides I and J, and stationary knives j , of the feed-wheels L, pro-

vided with dogs l , guides O, and supporting-wheels M, substantially as set forth. 10

Witness my hand this 16th day of May, 1887.

JOHN GREENWOOD.
